UNITED STATES PATENT OFFICE

2,158,390

OPEN MESH FABRIC

Herbert E. White, San Francisco, Calif., assignor
to The E. H. Edwards Company, a corporation
of California

Application February 11, 1938, Serial No. 190,068

7 Claims. (Cl. 189—82)

The present invention relates to open mesh wire fabrics.

The object of the invention is to provide a novel and improved form of fabric that has the many advantages of a woven fabric, but the production of which does not require a weaving operation. The open mesh fabrics that have heretofore been produced are of several types, one being built up of a succession of short cross wires laid upon parallel longitudinally extending wires. Another known type of mesh comprises continuous wires that are laid in diagonal manner back and forth across the width of the fabric and that form a plurality of superposed and separate layers of parallel strands. The mesh fabric of the present application is composed of a plurality of layers of strands that are so related to each other in the completed fabric as to form in effect an interweaving of the wires of the respective layers, resulting in a security of assembly of the fabric additional to the means that is employed to secure together the strands at their crossing points.

Reference is made to United States patents, Numbers 2,140,488 and 2,137,257, that respectively disclose apparatus and method for making the present fabric. As disclosed in the patents to which reference has been made, the fabric is manufactured by laying successively a plurality of sets of strands upon a tubular mandrel, the strands being laid spirally, those of each set being parallel, and the spirals in which the successive sets are laid being oppositely disposed so that the strands of adjacent sets cross each other. The tubular body of crossed strands is continuously laid upon the mandrel, and at one end the said body is continuously stripped from the mandrel in a direction axial thereof and is flattened by bringing together the walls into superposed relation. The strands during this flattening operation are maintained in continuous condition, and they are held against relative movement. The result of flattening the layers of spiral strands, is to convert each set laid on the mandrel into two layers of strands, the strands of each layer extending diagonally from edge to edge and the diagonals of the strands of one layer being in the direction opposite to that of the diagonals of the strands of the other layer. It will be appreciated that because the successively laid spirals are in opposite directions, the body after flattening will comprise a plurality of layers of strands, the strands of each layer extending diagonally across the body in the direction opposite to that in which the strands of the

adjacent layers extend. To complete the fabric, the strands of the different layers are secured together at some or all of their crossing points, as by welding.

The completed fabric is composed of layers of parallel strands, two layers having been formed from each set of strands that was laid on the mandrel, the strands of such two layers extending across the fabric in opposite diagonals, and the strands of the two layers being continuous, and passing from one layer to the other at the edges of the fabric. Inasmuch as more than one set of strands is laid upon the mandrel, the completed fabric consists of a multiple of two layers of strands in superposed relation, and the strands of any layer crossing the strands of the adjacent layer or layers. The strands are so laid that in the completed fabric, the strands of alternate layers lie between the strands of the other layers to the strands of which they are parallel.

The method of manufacture above mentioned produces a novel type of fabric in which certain of the strands, extending diagonally across the fabric in one direction, pass over and under the alternate strands that it crosses, and that are in other layers of the fabric, and this peculiarity gives to the fabric the appearance, strength and advantages of a woven fabric.

The above description has been made to render the following description of the drawings more readily understandable.

In the accompanying drawings:

Figure 1 is a plan view of a section of the fabric.

Figure 2 is a perspective view of a section of the fabric in process of manufacture, just prior to the point at which the two parts of the fabric are brought together into final position.

Figure 3 is a sectional view on the line 3—3 of Figure 2.

Figure 4 is a sectional view upon the line 4—4 of Figure 1.

Figure 5 is a plan view of a section of a slightly modified form of fabric.

Figure 6 is a perspective view of the fabric of Figure 5.

In describing the fabric as shown in the drawings, numerals have been applied to the strands of the respective layers beginning at the outer layer upon one side and progressing to the outer layer upon the other side. The fabric consists of two outer layers 1 and 4 respectively, and two inner layers 2 and 3. The strands 1 are parallel to the strands 3 and cross the strands 2 and 4. The strands 1 and 4 form the two outer layers of the fabric, and the strands 1 and 4 change

from one layer to the other at the edges of the fabric. The strands 2 of the one inner layer are continuous with the strands 3 of the other inner layer, the strands changing from one layer 5 to the other at each edge of the fabric and the strands 2 and 3 extending across the fabric in opposite diagonal directions.

The strands of the two outer layers cross upon the same sides at all crossing points, that is to 10 say, at each crossing point of the strands 1 and 4, the strands 4 are on the same side of the strands 1. Similarly, the strands 2 always cross the strands 3 upon the same side. Now strands 4 are parallel to strands 2 and they cross the 15 strands 3 upon opposite sides of the said strands 3. Similarly, strands 1 and 3 are parallel and they cross the strands 2 upon opposite sides of the strands 2. Therefore as one of the strands 3 extends across the fabric and crosses strands 20 2 and 4 alternately, it will pass over and under alternate crossing wires. In the same manner, one of the strands 2 extending across the fabric, alternately passes over the strands 3 and under the strands 1. This alternate passing over and 25 under crossing strands by the strands 2 and 3 gives to the fabric an appearance that is characteristic of woven fabric and gives to it qualities very much superior to those of fabrics that are made up of strands that are simply crossed.

30 Referring to Figure 1, and following one of the outer strands 1 across the fabric, it will be seen that the strand crosses all of the oppositely extending strands 2 and 4 upon one side, and at the edge of the fabric it changes to the other 35 outer layer and recrosses the fabric in the opposite diagonal direction as one of the strands 4, crossing all of the strands 1 and 3 upon the same side. Similarly following one of the strands 3 across the fabric, it will be seen that it is parallel to the strands 1, that it crosses the fabric 40 always on the same side of the strands 2, and always on the side of the strands 4 opposite to the side upon which it crosses the strands 2. In other words, the strands 3 pass between the 45 strands 2 and 4, and the strands 2 pass between the strands 1 and 3. Because the parallel strands 1 and 3 alternate, as do the parallel strands 2 and 4, the strands 2 and 3 pass alternately over and under the strands that they cross as above 50 described.

Because of this alternate over and under crossing of the strands, and the advantages that it imparts to the fabric, the fabric may aptly be termed "semi-woven".

55 In certain uses of open mesh fabric, it may be desirable to stay the fabric against longitudinal elongation. Figures 5 and 6 disclose a fabric so stayed. The stay strands 5 and 6 are located in the fabric between the two inner layers 60 composed respectively of the strands 2 and 3.

In the manufacture of this type of fabric, the stay strands may be led into the fabric during the operation of collapsing the fabric. The stay wires may be secured to the other wires of the 65 fabric at their crossing points in the same manner as the other crossing wires of the fabric are secured together.

As indicated in Figure 5, the stay strands may be disposed at any desired points in the width 70 of the fabric. They may be positioned to pass through a line of the crossing points of the diagonal wires, or they may pass along a line between the crossing points. Obviously the stay strands may be varied as to number and position or combination of positions.

The above-described fabric combines the advantages of a woven fabric and a fabric formed from, and consisting of, continuous strands, with the advantage of being manufacturable by methods other than weaving. The use of a process 5 to resist strains to which the fabric may be subjected, and what is more important, holds the fabric together in the event of failure of the welds or other means of securing together the strands at their crossing points. Another advantage 10 of the fabric from a standpoint of manufacturing and strength of finished product is that in smaller sizes of mesh, say in mesh of one-half inch, not all of the crossing points need be welded or otherwise secured, it being sufficient 15 if the crossing points between the outer layers 1 and 4 be secured, and the interweaving of the remainder of the strands will be sufficient to give an entirely satisfactory product.

From the foregoing, it is thought that the construction, operation, and many advantages of the herein described invention will be apparent to those skilled in the art without further description, and it will be understood that various changes in the size, shape and minor details of 20 construction may be resorted to without departing from the spirit or sacrificing any of the advantages of the invention.

What I claim is:

1. An open mesh fabric comprising an inner 35 flat fabric of crossed strands, and an outer fabric that surrounds the inner fabric, the said outer fabric comprising a plurality of continuous strands that extend continuously across the respective outer surfaces of the inner fabric and 40 change from one to the other of said surfaces at the edges of the inner fabric, the strands of the outer fabric lying wholly without the structure of the inner fabric throughout their extent, and the several strands being secured together at 45 points where they cross one another.

2. An open mesh fabric comprising an inner 50 fabric composed of a plurality of strands arranged in flattened spirals, and an outer fabric composed of strands arranged in flattened spirals 55 disposed oppositely to the spirals of the inner fabric and the inner fabric being located within the flattened spirals of the outer fabric, and the several strands being secured together at points at which they cross.

3. An open mesh fabric according to claim 2 and having longitudinally extending stay strands within the spirals of the inner fabric.

4. An open mesh fabric comprising an inner 60 mesh fabric composed of continuous parallel strands, each strand being disposed in alternate oppositely extending reaches, all of the reaches that extend in one direction crossing upon the same side of those extending in the other direction, and an outer fabric mesh composed of continuous strands arranged in alternate oppositely disposed diagonal reaches, the oppositely disposed reaches of the said outer fabric extending across the inner fabric on opposite sides thereof and being completely outside of the inner fabric, and the several strands being secured together at 65 points at which they cross.

5. An open mesh fabric according to claim 4, in which the respective reaches are diagonal and the diagonal reaches of the outer fabric are ar- 70 75

ranged upon the sides of the inner mesh upon which are the oppositely extending diagonal reaches of the inner mesh.

6. An open mesh fabric according to claim 4, in which the respective reaches are diagonal, the respective reaches of the outer fabric are parallel to those of the inner fabric, and the parallel strands of the respective fabrics are arranged in alternate relation.

7. An open mesh fabric according to claim 4, in which longitudinally extending stay strands are disposed between the respective reaches of the strands of the inner fabric, and all of the said stay strands are always upon the same sides of the respective strands of said inner fabric. 5

HERBERT E. WHITE.
